UNITED STATES PATENT OFFICE.

GOTTLOB BINDER, OF PHILADELPHIA, PENNSYLVANIA.

COLLAR-SEAM-DAMPENING MACHINE.

SPECIFICATION forming part of Letters Patent No. 657,388, dated September 4, 1900.

Application filed November 21, 1899. Serial No. 737,798. (No model.)

To all whom it may concern:

Be it known that I, GOTTLB BINDER, a citizen of the United States, residing in Philadelphia, Pennsylvania, have invented certain 5 Improvements in Collar-Seam-Dampening Machines, of which the following is a specification.

My invention relates to certain improvements in machines for dampening the seams 10 or fold-lines of collars, so that the collar can be readily turned.

The object of my invention is to construct a machine by which the moistening fluid is heated prior to its being applied to the collar, 15 as I find that warm water will penetrate the starch more readily than cold water heretofore used in this type of machine.

In the accompanying drawings, Figure 1 is a perspective view of my improved collar- 20 seam dampener. Fig. 2 is a side view drawn to an enlarged scale. Fig. 3 is a sectional view on the line 3 3, Fig. 2. Fig. 4 is a perspective view of the heat-conducting bar, and Fig. 5 is a sectional view of a detail of 25 Fig. 2.

It is difficult to properly turn down a lay-down or wing collar without first dampening the fold-line. Laundries at the present time use a dampening device with cold water or 30 dry steam; but when warm water is used I find that it will penetrate the starch which has previously been applied more readily than cold water or dry steam, but it is difficult to provide means for heating the water 35 to the proper temperature, as the least sputter of water will spot the collar. If a lamp be applied for the purpose near the dampener, the soot from the lamp is liable to fall upon the collar and soil it. By my improvements 40 I am enabled to heat the water at an even temperature and to keep the heating device away from the collar.

A is a stand, which may be of any form desired, and projecting from this stand is a bearing A', supporting a grooved wheel B, adapted to rotate on a screw b, by which it is held in place. Pivoted at a to the frame A is an arm D, carrying a reservoir D' for the water. This reservoir has a tubular extension E, (shown 45 clearly in the sectional view, Fig. 3,) and on the lower portion of the extension is a presser-foot e, which rests above the wheel B. The

presser-foot is grooved, as shown, to correspond to the groove in the wheel. The passage e' in the tubular extension is preferably 55 tapered, leaving a very small opening at the bottom for the water or other fluid to pass out over the fold-line of the collar as it is drawn over the wheel. The valve-rod e² is screwed into the portion e³ of the reservoir, and this 60 valve-rod has a groove cut on a taper, so as to allow for more or less liquid to pass through the passage e' to the collar. A cup e is provided to catch the drip, and the surplus water thus collected can be utilized again. Rig- 65 idly secured to the tubular depending portion is a rearwardly-extending bar F, (clearly shown in Figs. 4 and 5,) having a clamp f at one end by which it is confined to the depending portion E. The opposite end of the 70 bar has a notched flange f', adapted to the arm D, by which it is steadied. There is a space f² between the arm and the bar F. Directly back of this bar is a nozzle g of a Bunsen burner G. This burner is supported on 75 a bracket A², detachably secured to the frame A in the present instance. The burner passes through the bracket and is confined in position by a set-screw a', so that the nozzle g can be set any distance from the end of the 80 bar F as is desired.

g' is a gas-valve, and g² is a nipple, to which a gas-hose can be attached.

g³ is the air-inlet for the burner.

It will be seen by this construction that 85 when the reservoir D' is filled with water and the gas ignited at the nozzle g the gas-flame will strike upon the end of the bar F and a portion will pass through the space f² between the bar and the arm D, heating the 90 arm to a certain extent. The bar is preferably made of material which can be readily heated, such as brass or copper, and the heat will be transmitted to the tubular depending portion E, through which the water from the 95 reservoir must pass. The reservoir itself is slightly warm, owing to the heat applied upon the arm D, and the water is reheated as it passes down the channel e' to the presser-foot, the heat being sufficient to heat the water to 100 the temperature desired, so that when the water is applied to the collar it will immediately penetrate the starch at the fold-line and the collar can be readily folded.

I preferably provide a covering F', of non-conducting material, which incloses the main portion of the bar, leaving the two ends exposed, although this may be dispensed with 5 without departing from the main feature of my invention.

I claim as my invention—

1. The combination in a seam-dampener, of a support for the collar over which the collar 10 is drawn, a presser-foot, a reservoir, a passage leading from the reservoir to the presser-foot, and means for heating the water prior to its being applied to the fold-line of the collar, substantially as described.
- 15 2. The combination in a seam-dampener, of a frame carrying a wheel, a pivoted reservoir, a presser-foot carried thereby directly above the wheel, a passage leading from the reservoir to the presser-foot, and means for heating 20 the water prior to its being applied to the fold-line of the collar, substantially as described.
- 25 3. The combination in a seam-dampener, of a frame, a bracket, a wheel carried by the bracket, an arm pivoted to the frame, a reservoir carried by the arm, said reservoir having a tubular depending portion, a presser-foot at the end of the depending portion directly above the wheel, a bar secured to the 30 depending portion and so arranged that the gas-flame will heat the bar which will in turn heat the depending portion through which the water flows onto the collar, substantially as described.
- 35 4. The combination of a frame, a wheel carried thereby, a reservoir having a depend-

ing tubular portion, a presser-foot at the end of the depending portion, a bar secured to the depending portion, and extending rearwardly, a gas-burner having its nozzle directly back of the end of the bar so that the flame from the burner will strike the end of the bar, substantially as described. 40

5. The combination of a frame, a bearing, a wheel carried by the bearing, an arm pivoted to the frame, a reservoir carried by the arm, having a tubular depending portion and a presser-foot at the lower end of the tubular portion, a rearwardly-extending bar secured to the depending portion, a space between the 45 end of the bar and the arm, and a burner so situated in respect to the bar and arm that the flame from the burner will strike against the end of the bar and enter the space between the bar and the arm, substantially as 50 described.

6. The combination of a frame, a bearing, a wheel at the end of the bearing, an arm pivoted to the frame, a reservoir carried by the arm, a portion depending from the reservoir, 55 a grooved presser-foot carried thereby, a bar clamped to the depending portion and extending rearwardly, a burner for heating the bar and a non-conducting cover for the bar, substantially as described. 65

In testimony whereof I have signed my name to this specification in the presence of two subscribing witnesses.

GOTTLOB BINDER.
